UNITED STATES PATENT OFFICE.

LAUREL E. GIBSON, OF CLYDE, OHIO.

INTERNAL-COMBUSTION ENGINE.

1,182,267.

Specification of Letters Patent.

Patented May 9, 1916.

Application filed March 11, 1915. Serial No. 13,569.

To all whom it may concern:

Be it known that I, LAUREL E. GIBSON, a citizen of the United States, residing at Clyde, in the county of Sandusky and State of Ohio, have invented certain new and useful Improvements in Internal-Combustion Engines, of which the following is a specification.

The present invention relates to certain new and useful improvements in internal combustion engines and more particularly to a valve construction for a four cycle engine, the object of the invention being to provide a device of this character which embodies novel features of construction whereby the valve is automatically and accurately timed in its movements so as to cause a smooth running of the engine.

Further objects of the invention are to provide a valve mechanism which is strong and durable in its construction, which is positive in its action, which can be accurately timed so as to cause a smooth running of the engine, and which is not liable to break or get out of repair.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawing, in which:

Figure 1 is a vertical sectional view through a one cylinder engine embodying the principle of the invention, the piston being shown at the middle of the intake stroke. Fig. 2 is a similar view showing the piston at the middle of the compression stroke. Fig. 3 is a similar view showing the piston at the middle of the power stroke. Fig. 4 is a similar view showing the piston at the middle of the exhaust stroke. Fig. 5 is a detail view of the gearing between the crank shaft of the engine and the cam shaft. Fig. 6 is a detail sectional view of the cam wheel and the lower end of the valve actuating plunger. Fig. 7 is a plan view of the cam wheel with the cam groove divided into quadrants which are marked to designate the position of the engine piston when the particular quadrants are in operative position.

Corresponding and like parts are referred

to in the following description and indicated in all the views of the drawing by the same reference characters.

Specifically describing the present embodiment of the invention, the numeral 1 designates an engine cylinder within which a piston 2 is mounted so as to reciprocate back and forth in the usual manner. The conventional spark plug 3 is shown as applied to the cylinder head, and the piston is connected by the piston rod 4 to a crank shaft 5 which is journaled within a crank case 6.

Arranged at one side of the engine cylinder 2 and having a spaced and parallel relation thereto is a valve cylinder 7 which communicates at its lower end with the crank case 6, the latter being extended to one side for that purpose. Both the engine cylinder 1 and valve cylinder 7 may be surrounded by a suitable water jacket 8. A valve piston 9 is mounted to reciprocate within the valve cylinder 7 and has the base thereof pivotally connected at 10 to the upper end of a plunger 11 which extends downwardly into the crank case 6 and engages a cam wheel C which is keyed upon a cam shaft 12, said shaft being arranged substantially parallel to the crank shaft 5 of the engine and suitably journaled in the crank case 6. Arranged within the valve cylinder 7 at the base thereof is a pair of transversely disposed anti-friction rollers 13 which engage opposite sides 14 of the plunger 11 so as to hold the same against swinging movement.

The upper end of the engine cylinder 1 is connected to one side of the valve cylinder 7 by a port or passage 14 which is adapted to be closed or placed in communication with either the exhaust port 15 or the inlet port 16. The ports 15 and 16 communicate with the valve cylinder 7 on the opposite side thereof to the engine port 14 and the exhaust port 15 is in substantial alignment with the engine port 14 while the inlet port 16 is arranged below and parallel to the exhaust port 15. An exhaust pipe 17 is shown as communicating with the exhaust port 15, while a fuel supply pipe 18 is shown as leading from the carburetor 19 to the inlet pipe 16.

The valve piston 9 is provided at the upper end thereof with a packing ring 20 which is of sufficient width to close and tightly seal the orifice of the engine port

14 when the valve piston is in the position assumed during the compression and power strokes of the engine piston, as indicated by Figs. 2 and 3. Upon a continued downward movement of the valve piston 9 the upper end thereof will uncover the opposed orifices of the engine port 14 and exhaust port 15 so that the two ports communicate with each other and the burnt gases within the engine cylinder can be discharged through the exhaust pipe. This is the position assumed by the valve piston during the exhaust stroke of the engine piston, and is illustrated by Fig. 4.

15 Extending transversely through the valve cylinder 9 is a diagonally disposed passage 21 which is adapted to establish communication between the engine port 14 and the intake port 16 when the valve piston 9 is at the upper limit of its movement and the engine piston 2 is on the intake stroke, as illustrated by Fig. 1. The exhaust port 15 is then closed by the valve piston 9.

16 The cam shaft 12 is geared to the crank shaft 5 of the engine so that the former makes one complete revolution for each two revolutions of the latter. In the present instance the crank shaft 5 is shown as provided with a pinion 22 which meshes with a 25 pinion 23 upon the countershaft 24, the latter in turn meshing with a gear wheel 25 which is rigid with the cam shaft 12. The cam wheel C is provided upon both sides thereof with correspondng annular cam 30 grooves 26 which receive rollers 27 journaled upon the arms of the bifurcated lower end 11^a of the plunger 11. The cam grooves 26 are divided as near as possible into quadrants which are brought successively into 35 operative position for the various piston strokes of each cycle. The quadrant 26^a is spaced the farthest from the cam shaft 12 and is in operative position during the intake stroke of the engine cylinder, as indicated by Fig. 1, the piston valve 9 being then at the upper limit of its movement so that the diagonal passage 21 through the same establishes communication between the engine port 14 and the intake port 16. The 40 quadrant 26^b next comes into operative position and lowers the valve piston 9 so that the packing ring 20 at the upper end thereof closes the engine port 14 and exhaust port 15. This is the compression stroke of the engine and the engine port is tightly sealed. The quadrant 26^c which follows the quadrant 26^b is a continuation of the latter and is spaced the same distance from the cam shaft 12 so that there is no change in the position of the valve piston 9. This third 45 quadrant 26^c comes into action during the power stroke of the engine piston and holds

the valve piston 9 in position to seal the engine port during this power stroke. The quadrant 26^a comes into action after the 50 quadrant 26^c and is located the closest to the cam shaft of any of the quadrants. This quadrant 26^a moves the valve piston 9 to its lower limit of movement so that the exhaust port 15 communicates with the engine port 14 through the top of the valve cylinder. This is the position of the valve piston during the exhaust stroke of the engine piston, as illustrated by Fig. 4. The various quadrants of the annular cam grooves are all concentric and have the axis of the cam shaft 12 as a center, and these quadrants are connected at their ends so as to produce a quick shifting of the valve piston.

55 For the purpose of illustrating the principle of construction as clearly as possible in its simplest form, the invention has been shown as embodied in a single cylinder engine, although it will be obvious that it is equally well adapted to be embodied in 60 multi-cylinder engines, and that the proportions and various sizes of the parts can be varied as found necessary.

Having thus described the invention, what I claim as new and desire to secure by Letters Patent, is:—

65 The combination with an engine cylinder provided with a port and having a piston mounted therein, of a valve cylinder provided in one side thereof with an engine port communicating with the port of the cylinder, and in the opposite side thereof with an exhaust port and an intake port, one of which is in alinement with the engine port, a valve piston mounted within the 70 valve cylinder and adapted to uncover the engine port and the port in alinement therewith to establish communication between the two ports through the valve cylinder, said valve piston being formed with 75 a transverse passage adapted to establish communication between the engine port and the other of the before mentioned ports at another position of the valve piston, a packing ring applied to the end of the 80 valve piston and being of sufficient width to seal the ports in alinement with each other at another position of the valve piston, and cam means driven by the engine piston for automatically shifting the valve piston into 85 its proper consecutive positions during the operation of the engine.

90 In testimony whereof I affix my signature in presence of two witnesses.

LAUREL E. GIBSON.
